JOHN A. SPENCER, OF NEWTON, MASSACHUSETTS, ASSIGNOR TO RAYTHEON PRODUCTION CORPORATION, OF NEWTON, MASSACHUSETTS, A CORPORATION OF DELAWARE

STEM AND METHOD AND MEANS FOR MAKING SAME

Application filed October 7, 1929. Serial No. 397,861.

This invention relates to stems for use in vacuum tubes and the like, and to methods and means for manufacturing them. In the manufacture of a stem having a press of cruciform cross-section, it has been customary to use four anvils, each of said anvils approximating the shape of a quadrant. The direction of force applied to these anvils substantially bisected each of them. In manufacturing stems in this manner it was found that the friction of the glass against the anvil tended to crowd the glass toward the center. A further evil effect was the failure of the anvils to exert sufficient pressure normal to the glass at the ends of the wings with the result that wires sealed therein were not gas-tight. Such effects were often exaggerated by the unavoidable variations in the temperature of the glass due to a change in adjustment of the burners, gas pressure or direction of flame.

An object of this invention is to devise a method of manufacturing stems having a cruciform press which will be free of the above noted defects.

A further object is to devise simple and suitable mechanism for use in the manufacture of such stems.

In general the stems are manufactured in the usual stem head and equipped with four anvils instead of the customary two. The anvils are so shaped and impelled with respect to each other and to the glass that each one tends to press the glass throughout the full extent of a wing surface against an adjacent anvil. This is accomplished by so shaping the anvils that as they are pressed in toward the glass they tend to lock and twist around.

Referring to the drawings, Figure 1 is a view in elevation of a stem head.

Figure 2 is a diagrammatic view showing the anvils in position after pressing the soft glass.

Fig. 3 is a view of the completed stem. The stem head shown in Figure 1 comprises the usual jaws 1 and 2 between which is clamped a glass tube 3 out of which the stem is to be made. Within this tube are a plurality of wires 4 suitably positioned by holes in

a jig 5. An exhaust tube 6 is maintained in position by the well known mechanism, generally designated as 7. Handles 8 and 9 are provided for releasing jaw 1 and 2 and mechanism 7 respectively. Supported in spaced position equi-distant around the glass tube are four arms 10, 11, 12 and 13. These arms pivoted at 16 and are adapted to be actuated through push rods 17 and spider 18 by push rod 19 passing through the center of the head and operated in the usual manner.

Supported by arms 10 to 13 inclusive are four anvils 21 to 24 inclusive. These anvils are of usual thickness and the shape shown in Figure 2. The anvils comprise portions 26 having the rectangular shape shown. Portions 26 are backed by a larger portion 28 of the anvil having sloping sides 29 and 30 coming from the rectangular sides of portion 26. In practice, the best results have been secured by making the angle between side 29 and the adjacent side of portions 26, 117°. The same angle is taken between side 30 and the corresponding side of portion 26. In this way, it is evident that sides 29 and 30 are perpendicular to each other. Of course any other angles may be chosen providing the same relationship is maintained.

The center lines passing through the angles and intersecting at the central portion of the press indicate the direction in which force is applied to the anvils. The angle between the direction of applied force and the horizontal axis of the press is 15°.

With a head equipped with such anvils it is evident that as the anvils are pressed toward the glass that the sloping sides 29 and 30 of all the anvils tend to deflect or twist the anvils in a clockwise direction as seen in Figure 2. This deflection is naturally very small but is just sufficient to permit one of the sides of portion 26 to press the glass perpendicularly to its plane against the side of an adjacent anvil. In this way it has been found that the glass throughout the press is uniformly and firmly pressed to form tight seals.

In Figure 3 a completed stem is shown and comprises flared tubular portion 35 with a press having wings 36, 37, 38 and 39 formed therein. The usual exhaust tube 40 is also

shown. Sealed into wings 36 to 39 inclusive are heavy arbors 40, while smaller wires 41 are sealed in the central portion of the wings. As many wires as may be found necessary 5 may be sealed in the press without fear of leakage at the seals.

I claim:

1. The method of making stems having cruciform presses which comprises pressing 10 the glass inwardly toward the center to form wings and then pressing the glass normal to the wing sides with different pressures.
2. The method of forming stems having cruciform presses which consists in pressing 15 the glass inwardly to form wings, the axis of pressure being nearer to one wing surface than to the adjacent wing surface, and then pressing the glass in a direction normal to the sides of the wings.
3. The method of forming stems having cruciform presses which consists in applying 20 pressure from four points inwardly against the glass to form wings, the axis of pressure at each point being at an angle of substantially 15° to an adjacent wing face and then applying pressure to the winged sides in the direction normal to the plane thereof.
4. In a head for making stems having a cruciform press, a plurality of anvils, each 25 of said anvils having a forwardly projecting portion adapted to shape the glass, a rear portion adapted to cooperate with adjacent anvils to exert pressure on the glass and means for pressing each of said anvils toward the center of the head along axes having dissimilar angles with horizontal axes of the press.
5. In a head for making stems having a cruciform press, a plurality of anvils, each 30 of said anvils having a forwardly projecting portion for shaping the glass, a rear portion adapted to cooperate with adjacent anvils to exert pressure on the glass, and means for pressing the anvils toward the center of the 35 heads along the axis at an angle of substantially 15° with the horizontal axes of the press.
6. In a head for making stems with a cruciform press, a plurality of anvils, each of 40 said anvils having a forwardly projecting portion having faces at substantially right angles to each other, and a rear portion, said rear portion being bounded by faces adjacent said first two faces, said bounding faces 45 being at right angles to each other in each anvil.
7. In a head for making stems having a cruciform press, a plurality of anvils, each of 50 said anvils having a forwardly projecting portion having rectangularly disposed side faces, a rear portion, and bounding faces for said rear portion extending from the ends of 55 said rectangularly disposed side faces, said bounding faces having an angle of 117° with 60 said side faces.

8. In a head for making stems having cruciform presses, a plurality of anvils, each of said anvils having a forwardly projecting glass shaped portion and a rear portion adapted to cooperate with adjacent anvils, 70 said rear portions being so shaped that radial pressure on the anvils tends to induce circular strain in the anvils.

9. The method of forming stems having cruciform presses which consists in pressing the glass inwardly to form wings, the axis of pressure first being maintained predominantly normal to one surface of each wing, 75 said axis of pressure being finally shifted to a position so that the proportion of pressure on the opposite surface of each of said wings is substantially increased.

10. In a head for making stems with a multiple wing press of a glass-like material, 80 a plurality of anvils arranged to be invariably moved toward each other and having faces for engaging a glass-like body to form wings therein, each anvil having two wing faces differently inclined to the direction of 85 their inward movement.

11. In a head for making stems with a multiple wing press of a glass-like material, 90 a plurality of anvils arranged to be invariably moved toward each other and having faces for engaging a glass-like body to form wings therein and compress said wings to a predetermined thickness, wing faces being 95 differently inclined to the direction of their inward movement to cause the anvil face engaging one face of a wing to move relatively thereto at greater velocity than the anvil face engaging the other face of the wing.

12. In a head for making stems with a multiple wing press of a glass-like material, 100 a plurality of anvils arranged to be invariably moved toward each other and having each a pair of anvil faces for engaging a glass-like body to form wings therein and compress said wings to a predetermined thickness, each anvil having two wing faces 105 differently inclined to the direction of their inward movement to cause one anvil face to move against the engaged wing face in formation at a different rate than its other anvil face moves against the wing face engaged 110 by it.

13. In a head for making stems with a multiple wing press of a glass-like material, 115 a plurality of anvils arranged to be invariably moved toward each other and having faces for engaging a glass-like body to form wings therein and compress said wings to a predetermined thickness, and means on said anvils for interlocking the same against each other in the inward end position.

14. In a head for making stems with a multiple wing press of a glass-like material, 120 a plurality of anvils arranged to be invariably moved toward each other and having faces for engaging a glass-like body to form wings 125

therein and compress said wings to a predetermined thickness, and means on said anvils for interlocking the same against each other in the inward end position to uniformly distribute the pressure of the anvil faces on the formed wing faces.

15. In a head for making stems with a multiple wing press of a glass-like material, a plurality of anvils arranged to be invariably moved toward each other and having faces for engaging a glass-like body to form wings therein and compress said wings to a predetermined thickness, wing faces being differently inclined to the direction of their 15 inward movement to cause the anvil face engaging one face of a wing to move relatively thereto at greater velocity than the anvil face engaging the other face of the wing, and means on said anvils for interlocking the 20 same against each other in the inward end position to uniformly distribute the pressure of the anvil faces on the formed wing faces.

16. In a head for making stems with a multiple wing press of a glass-like material, 25 a plurality of anvils arranged to be invariably moved toward each other and having each a pair of anvil faces for engaging a glass-like body to form wings therein and compress said wings to a predetermined 30 thickness, each anvil having two wing faces differently inclined to the direction of their inward movement to cause one anvil face to move against the engaged wing face in formation at a different rate than its other anvil 35 face moves against the wing face engaged by it, and means on said anvils for interlocking the same against each other in the inward end position to uniformly distribute the pressure of the anvil faces on the formed 40 wing faces.

17. The method of making stems with a multiple wing press of glass-like material which comprises impressing a plurality of anvils inwardly into a softened glass-like 45 body of the stem to form wings therein, and directing the inward movement of said anvils to cause one face of a wing to be engaged by an anvil surface moving at greater speed than the anvil surface engaging the other 50 face of the wing.

18. The method of making stems with a multiple wing press of glass-like material which comprises impressing a plurality of anvils inwardly into a softened glass-like 55 body of the stem to form wings therein, directing the inward movement of said anvils to cause one face of a wing to be engaged by an anvil surface moving at greater speed than the anvil surface engaging the other 60 face of the wing, and then impressing with said anvils substantially uniform pressure on all wing faces.

In testimony whereof, I have signed my name to this specification.
